UNITED STATES PATENT OFFICE.

CHARLES B. CULVER AND JOSEPH A. HECKARD, OF SEASIDE, OREGON.

TURBINE.

No. 909,369.

Specification of Letters Patent.

Patented Jan. 12, 1909.

Application filed October 12, 1908. Serial No. 457,418.

To all whom it may concern:

Be it known that we, CHARLES B. CULVER and JOSEPH A. HECKARD, residing at Seaside, in the county of Clatsop and State of Oregon, have invented certain new and useful Improvements in Turbine-Engines; and we do hereby declare the following to be a full, clear, and exact description of the invention, such as will enable others skilled in the art to which it appertains to make and use the same.

This invention relates to impact turbine engines which are provided with steam jets; and it consists in the novel construction and combination of the parts hereinafter fully described and claimed.

In the drawings, Figure 1 is an end view of the engine showing a portion of the casing in section. Fig. 2 is a vertical section of a portion of the engine, taken on the line $x-x$ in Fig. 1, and drawn to a larger scale. Fig. 3 is a detail view of a portion of one of the plates, showing a portion of the steam-chest in section. Figs. 4 and 5 are detail plan views, partly in section, of certain of the blades, showing them arranged for forward and for rearward motion respectively. Fig. 6 is a cross-section through the steam-chest, taken on the line $y-y$ in Fig. 3.

30 A is the cylindrical casing of the engine, provided with end-plates B having steam channels or passages b. The casing is provided with an annular partition-plate C secured to its periphery and arranged parallel to the end-plates B. This partition-plate C is provided with a steam-chamber or passage c. Only one partition plate is shown, but as many of them as desired may be used, and this partition-plate divides the 35 casing into two cylinders D and E.

The steam to drive the engine is admitted through a main steam-pipe d provided with branch-pipes d' which are connected to the passages b and c, and are provided with regulating valves of any approved construction. After having expanded and done its work in the cylinders D and E, the steam is let out through the exhaust-pipe e. The partition-plate C has holes e' near its periphery to 45 permit the exhaust steam of one cylinder to mix with the exhaust steam of the other cylinder and pass out by the exhaust-pipe.

F and G are two rotors secured side by side upon a driving-shaft H, and arranged to 50 work in the cylinders D and E respectively. The shaft H passes centrally through the

casing and is journaled in bearings h of approved construction. These bearings are provided with adjusting-devices or screws h', and are preferably of the kind known as 60 thrust-bearings, so that the shaft H may have no endwise movement. The hubs of the rotors extend under the partition-plate C.

Each end-plate and partition-plate has a similar steam-chest I, and the description is 65 therefore confined to one of them. The steam-chest I is an annular chamber arranged near the hub of the rotor, and connected to the steam-passage pertaining to it by a port or ports i. The outer wall of the 70 steam-chest consists of a ring of curved nozzles formed of blades J having flanges j which are secured to the plate.

K is a valve consisting of a ring provided 75 with a series of holes k. This ring-valve is mounted in the steam-chest under the nozzles so that the amount of steam passing through the nozzles can be regulated or cut off by oscillating the said valve circumferentially. This valve is operated by means of a rod L 80 which passes through a stuffing-box on one of the steam-pipes and which is connected to a short connecting-bar or rod k'. The bar k' is secured to a lug on the valve, and it projects through the steam-port into the steam-chest. The rod L can be operated by hand, 85 or it can be operated automatically by any approved form of speed-governor. The steam-pipes are arranged a little above the centers of the cylinders so that the rods L 90 work horizontally.

Each plate is provided with a series of stationary blades m, and each rotor is provided with a series of power blades n. The blades m have beveled flanges m' at their bases, and the blades n have beveled flanges n'. Rings p are provided for securing the flanges m' and j to the plates, and similar rings p' are provided for securing the flanges n' to the rotors. These rings have beveled surfaces 95 to fit the beveled ends of the flanges, and they are secured to the plates and rotors by fastening-devices o, such as rivets. The blades are all arranged and adjusted in their correct positions before the fastening devices are tightened to clamp them in position.

The power blades m are shaped like blunt wedges in cross-section. They have troughs 2 in their flanks, and their faces 3 are rounded on circular arcs of less radius than the troughs 2, so that a series of passages 4 is 100 105 110

formed between the blades. These passages are narrowest at the middle parts of the troughs, and increase in area on each side of the blades. The sides of the blades *m* are 5 inclined with reference to their circular path of rotation.

The stationery blades *n* are shaped something like sickles in cross-section, and their outer sides have straight extensions 6 which 10 converge to points, and which are arranged substantially parallel to the adjacent sides of the power blades *m*.

A series of curved jet passages 7 is formed between the flanks 8 and the faces 9 of the 15 stationary blades *m*, and these passages 7 converge gradually from their inlets to their outlets.

All the blades are of the same length, but 20 those near the shaft are smaller than those remote from it. The blades increase in breadth, thickness and area of cross-section, in a regular proportion, as they increase in distance from the shaft, each circle of blades having the same number of blades in it. The 25 passages between the blades increase in area in a similar manner, being smallest near the shaft.

The peculiar shape of the stationary blades *m*, and their arrangement in concentric circles, enables the said blades to deflect the 30 steam to the most effective angle, and cause it to impinge against the troughs in the flanks of the next series of power blades. This gives the engine great efficiency, and enables 35 it to start under heavy loads. The steam is permitted to expand in passing from the passages 4 into the next series of passages 7 so that there is but little back pressure. The steam is expanded step by step as it passes 40 through the rings of blades from the nozzles of the steam-chest to the exhaust space at the periphery of each cylinder, so that it is used in an economical and efficient manner.

In the engine shown in Fig. 2, the casing is 45 divided into four sections I, II, III, and IIII. Each section has similar rings of stationary blades *m*, and intercurrent rings of power blades *n* working between them. Each of the said sections has its own steam-chest and 50 admission-valve *K*, and each section is capable of being operated independent of the others. As turbine engines of this type are most economical when working under full steam pressure, this arrangement is very ad- 55 vantageous. The end thrusts of the two end sections I and IIII are balanced, and also the end thrusts of the two middle sections. When the load is materially decreased, one pair of sections is cut out automatically, or 60 by hand, by means of the valves *K*, so that the remaining pair of sections operates under full steam pressure. Slight variations of load are met by partially closing one or more of the valves *K*.

When the engine is used as a non-reversing 65 engine, all the blades are arranged in the same direction, and so that there is no material end thrust on the shaft. When the engine is required for use as a reversing engine, one pair of sections I and IIII can have 70 blades arranged in one direction as shown in Fig. 4, and the other pair can have its blades arranged in the reverse direction as shown in Fig. 5. With this form of engine there is also no material end thrust. When the engine is used as a marine engine to drive a propeller, the blades in sections II and IIII can be 75 arranged in the same direction to balance the thrust of the propeller when going ahead; and the blades in sections I and III can be 80 arranged in the reverse direction to balance the pull of the propeller when going astern. If greater power is desired for driving the propeller ahead, additional steam cylinder sections and rotors can be provided accord- 85 ingly.

What we claim is:

1. In a turbine engine, the combination, 90 with a flat supporting plate, of blades provided with base flanges, flat rings engaging with the said flanges, and fastening devices which secure the said rings against the flat side surface of the said plate and thereby clamp the said blades in position.

2. In a turbine engine, the combination, 95 with a flat supporting plate, of blades provided with base flanges having beveled portions, flat rings having beveled surfaces which engage with the beveled portions of the said flanges, and fastening devices which 100 secure the said rings against the flat side surface of the said plate and thereby clamp the said blades in position.

3. In a turbine engine, the combination, 105 with a rotor provided with a series of laterally-projecting blades arranged in a ring and forming a series of steam passages which are narrowest at their middle parts, each of the said blades having converging side portions, a trough in its flank and a rounded face; of a 110 stationary plate provided with a series of laterally-projecting blades arranged in a ring inside the ring of rotor blades and forming a series of converging passages for delivering jets of steam to the troughs of the 115 rotor blades.

4. In a turbine engine, the combination, 120 with a rotor provided with a series of laterally-projecting blades arranged in a ring and forming a series of steam passages, each of the said blades having a side portion inclined with reference to its path of rotation and having a trough in its flank; of a stationary plate provided with a series of laterally-projecting blades arranged in a ring inside 125 the ring of rotor blades and provided with extensions inclined in a similar manner to the adjacent side portions of the rotor blades,

and forming a series of converging passages for delivering jets of steam to the rotor blades.

5. In a turbine engine, the combination, with a rotor provided with a series of laterally-projecting blades arranged in a ring and forming a series of steam passages, each of the said blades having a side portion inclined with reference to its path of rotation 10 and having a trough in its flank; of a stationary plate provided with a series of laterally-projecting blades arranged in a ring inside the ring of rotor blades and provided with extensions inclined in a similar manner 15 to the adjacent side portions of the rotor blades and forming a series of curved converging passages, each stationary blade being substantially sickle-shaped in cross-section and having a straight and pointed 20 tension.

6. In a turbine engine, the combination, with a rotor provided with laterally-projecting blades having troughs in their flanks and arranged in concentric rings, of a stationary 25 plate provided with blades also arranged in rings and projecting laterally between the aforesaid rings and forming curved and converging steam jet passages, all the said blades being of the same length and increasing in 30 width and breadth in proportion to their distance from the center of rotation.

7. In a turbine engine, the combination, with a cylinder provided with a plate having a series of laterally-projecting blades, and 35 having also an annular and stationary steam-chest arranged near its center and provided with a series of steam-jet nozzles at its periphery, of a rotor provided with a series of blades which project between the cylinder 40 blades, a ring-valve provided with steam-passages and mounted inside the said steam-chest, and means for oscillating the said valve to regulate the flow of steam through the said nozzles.

45 8. In a turbine engine, the combination, with a cylinder provided with a plate having a series of laterally-projecting blades, and having also a steam-passage and an annular steam-chest, said steam-chest being arranged 50 around the center of the cylinder and provided with a series of steam-jet nozzles, of a rotor provided with a series of blades which project between the cylinder blades, a ring-valve provided with steam-passages and 55 mounted inside the said steam-chest, a steam supply-pipe connected with the said steam-passage and steam-chest, and rods for oscillating the said ring-valve arranged in the said steam-passage and steam supply-pipe.

60 9. In a turbine engine, the combination, with a casing having a plurality of cylinder sections arranged side by side and provided with laterally-projecting blades arranged in

rings, of a driving-shaft journaled at the axis of the said casing, a plurality of rotors 65 secured on the said shaft and arranged in the said cylinder sections and provided with blades which run between the cylinder blades, annular steam-chests provided with nozzles and arranged in each of the said cylinder sections around the said shaft, and a separate valve for each steam-chest which regulates the passage of steam through its nozzles into the cylinder section pertaining to it. 75

10. In a turbine engine, the combination, with a casing provided with an annular partition-plate secured to its periphery and provided with an exhaust-passage, said plate and casing being provided with laterally-projecting blades arranged in rings, of a driving-shaft journaled at the axis of the said casing, rotors secured on the said shaft and arranged in the casing and provided with blades which run between the aforesaid 85 blades, annular steam-chests provided with nozzles and arranged one in each section of the said casing, and a separate valve for each steam-chest which regulates the passage of steam through its nozzles into the section of 90 the cylinder pertaining to it.

11. In a turbine engine, the combination, with a casing having a plurality of sections arranged side by side and provided with laterally projecting blades, of a driving shaft 95 journaled at the axis of the said casing, a plurality of rotors all secured to the said shaft and arranged in the said sections and provided with laterally projecting blades, and a separate valve for admitting steam of 100 prearranged pressure to each of the said sections, whereby the number of sections in operation may be varied according to the power required without changing the pressure.

12. In a turbine engine, the combination, 105 with a casing having a plurality of sections arranged side by side and provided with laterally projecting blades, of a driving shaft journaled at the axis of the said casing, a plurality of rotors all secured to the said shaft 110 and arranged in the said sections and provided with laterally projecting blades, certain of the said sections and rotors having their blades arranged for forward motion and the remainder having their blades arranged 115 for rearward motion, and a plurality of steam admission valves connected to the said sections and operated independently so that the engine can be driven forward or backward.

In testimony whereof we affix our signatures, in presence of two witnesses.
